UNITED STATES PATENT OFFICE

2,535,698

ELECTRIC VALVE EXCITATION CIRCUIT

August Schmidt, Jr., Schenectady, N. Y., assignor
to General Electric Company, a corporation of
New York

Application December 28, 1949, Serial No. 135,352

1 Claim. (Cl. 315—274)

1

This invention relates to electric valve excitation circuits and more particularly to an excitation circuit for continuously exciting electronic devices utilizing an ionizable medium.

For certain purposes, it is desirable to excite continuously the ionizable medium used in electronic devices such as ignitron tubes. In order to maintain the cathode spot, it has been necessary to supply a relatively large current to the holding anode element such as is utilized in devices of the mercury pool cathode type. Ordinarily this large current would be larger than would be necessary under normal conditions to maintain the cathode spot in order that the spot would be maintained during abnormal conditions. Such large currents either require an excitation circuit made up of relatively large component parts or are characterized by high energy losses in the circuit.

An object of this invention is to provide static means for controlling in a precise fashion the excitation of a continuously energized electronic device having an enclosing envelope containing an ionizable medium.

Another object of the invention is to provide automatically operable means for limiting the energy required to maintain continuously the cathode spot in an electronic device of the type which utilizes an ionizable medium such as mercury.

Still another object of the invention is the provision of an arrangement for automatically reestablishing the excitation of an electronic device of the continuously excited ionizable medium type should the device momentarily become de-energized.

In accordance with my invention, the flow of current from the holding anode of the cathode spot is utilized to control a variable impedance connected in series with the ignitor element and the components are arranged so that the impedance in series with the ignitor is promptly decreased by a substantial amount should current cease to flow from the holding anode to the cathode. In this way, the ignitor is promptly re-energized and the cathode spot reestablished.

While I have shown my invention as applied to an electronic device of the well known ignitron type, it will be understood that it is not limited thereto and that the invention can be used in conjunction with any electronic device having an enclosing envelope with an ionizable medium and a holding anode disposed therein.

My invention will best be understood by reference to the accompanying drawing in which the

2

numeral 1 represents the enclosing envelope of an electron device of the ignitron type. A metallic closure 2 is joined to the envelope 1 through insulating ring 3. Closure 2 forms a part of the cathode. Also disposed within the envelope are a main anode 4, a control grid 5, a holding anode 6 and an ignitor 7.

As is well known, flow of current through the ignitor circuit vaporizes the mercury pool contained in metallic closure 2 and the spot so established on the mercury pool is maintained by the holding anode 6 which is of such a potential with respect to the cathode that a flow of electrons is maintained from the cathode to the anode 6.

For energizing ignitor 7, a transformer 8 energized from a source of alternating current potential 9 is used. The secondary winding of transformer 8 is arranged in series with the ignitor 7, and a unidirectional conducting device 10 prevents the flow of current from ignitor 7 to transformer 8 through device 10. Also included in the excitation circuit for ignitor 7 is a winding 11 forming a part of a variable reactor 12 having a magnetizing winding 13 and a control winding 14. Direct current potential for the holding anode 6 is supplied by rectifier 15 and transformer 16 from the alternating current supply 9. A suitable current limiting resistor 17 is connected in series with the holding anode 6.

The magnetizing winding 13 and the holding winding 14 are oppositely wound and are constructed of a proper number of turns so that the magnetomotive force produced by winding 13 is partially or completely offset by the magnetomotive force of winding 14 if holding anode 6 and its associated circuit is conducting a current, i. e. when a cathode spot is being maintained on the surface of the mercury pool. Magnetizing winding 13 is constructed so that the reactor 12 will become saturated should a current cease to flow in winding 14. In this way, the reactance of winding 11 is substantially reduced upon failure of current to flow from holding anode 6 to the mercury pool. This substantial reduction in the overall impedance of winding 11 results in a relatively large current through ignitor 7 and its associated circuit from the secondary of transformer 8. This large current is of sufficient magnitude to reestablish the cathode spot should the holding anode fail momentarily to maintain this spot.

Since the arrangement shown in the drawing and described thus far is capable of automatically reestablishing the cathode spot, it is not

necessary to supply a large current through the holding anode 6 and its associated circuit. Thus a minimum of current is required through this circuit and the component parts thereof can be of a relatively small size without incurring substantial energy losses in the holding anode circuit.

While I have shown and described a particular embodiment of my invention, it will be obvious to those skilled in the art that various changes and modifications may be made without departing from my invention in its broader aspects, and I, therefore, intend in the appended claim to cover all such changes and modifications as fall within the true spirit and scope of my invention.

What I claim as new and desire to secure by Letters Patent of the United States is:

In combination, an electric discharge device of the type employing an enclosing envelope and comprising therein an ionizable medium, a cathode, an ignitor, and a holding anode, an en-

ergizing circuit connected to said ignitor for causing the emission of electrons by said cathode, saturable impedance means connected in said circuit, means including a source of direct current for energizing said holding anode, a magnetizing winding energized with direct current and effective to saturate said impedance means, and a control winding the energization of which is dependent upon the flow of current from said holding anode to said cathode for opposing the magnetizing effect of said magnetizing winding.
